US0D1065120S

(12) **United States Design Patent** (10) **Patent No.:** **US D1,065,120 S**
(45) **Date of Patent:** **** Mar. 4, 2025**

(54) **ELECTRONIC DEVICE**

- (71) Applicant: **Samsung Electronics Co., Ltd.**, Suwon-si (KR)
- (72) Inventors: **Jooho Seo**, Suwon-si (KR); **Donghun Kim**, Suwon-si (KR); **Jaehyuk Lee**, Suwon-si (KR)
- (73) Assignee: **Samsung Electronics Co., Ltd.**, Suwon-si (KR)
- (**) Term: **15 Years**
- (21) Appl. No.: **29/767,018**
- (22) Filed: **Jan. 20, 2021**

(30) **Foreign Application Priority Data**

Aug. 7, 2020 (KR) 30-2020-0036814

(57) **CLAIM**

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another front perspective view thereof showing an upper portion of the electronic device rotated in relation to a lower portion;

FIG. 10 is another top view thereof showing an upper portion of the electronic device rotated in relation to a lower portion; and,

FIG. 11 is another rear perspective view thereof showing an upper portion of the electronic device rotated **180** degrees in relation to a lower portion.

The horizontal broken line shown in FIG. 10 illustrates environment. The remaining broken lines in the figures depict portions of the electronic device which form no part of the claimed design.

1 Claim, 9 Drawing Sheets
